UNITED STATES PATENT OFFICE.

JOHN H. PHILLIPS, OF NEW YORK, N. Y.

BOILER-FEEDER.

SPECIFICATION forming part of Letters Patent No. 289,704, dated December 4, 1883.

Application filed May 17, 1883. (No model.)

To all whom it may concern:

Be it known that I, JOHN H. PHILLIPS, of the city, county, and State of New York, have invented a new and Improved Boiler-Feeder, 5 of which the following is a full, clear, and exact description.

The object of my invention is to provide a new and improved boiler-feeder, which can be placed a distance from the boiler, and above 10 or below the water-line, and which will return all condensed water formed in the pipes or otherwise back to and into the boiler under any head or pressure of steam in the boiler.

The invention consists in a pump connected 15 with a vessel for receiving water, which vessel is provided with a float adapted to throw a weighted lever for adjusting the slide-valve of the steam-cylinder of the pump, whereby the pump will be started as soon as the water 20 in the vessel rises to a certain level.

The invention also consists in various parts and details and combinations of the same, as will be fully described and set forth herein-after.

Reference is to be had to the accompanying 25 drawings, forming part of this specification, in which similar letters of reference indicate corresponding parts in all the figures.

Figure 1 is a side view of my improved 30 steam-trap, parts being broken away and others shown in section. Fig. 2 is a plan view of the same. Fig. 3 is a longitudinal sectional elevation of the steam-chest and slide-valve in the same.

A vessel, A, of any desired shape, is provided with pipe B, for conducting the condensation water into the vessel, and with an outlet-pipe, C, for conducting off the water of condensation, which outlet-pipe C is connected 40 with the cylinder D of a pump, and has check-valves E E at each side of the connection with the pump-cylinder D.

The pump-piston F is fastened to the lower 45 end of a piston-rod, G, the upper end of which is fastened to a piston in a steam-cylinder, H, provided with a steam-chest, J, containing a slide-valve, K, provided with rods L L' passing through the stuffing-boxes in the top and bottom, respectively, of the steam-chest. The 50 exhaust-steam from the steam-chest J is conducted by a pipe, M, into the vessel A.

To the upper end of the piston-rod G, pro-

jecting over the top of the cylinder H, an arm, N, is fastened, which projects downward at the side of the cylinder H, and is provided 55 with two tappets, O O', separated a suitable distance. It is also provided at its lower end with a recessed lug, m, sliding on a vertical guide-bar, n, on the side of the cylinder H.

A shaft, P, is journaled in standards P' on 60 the top of the vessel, and the shaft is provided with an upwardly-projecting arm, Q, and a downwardly-projecting curved arm, Q', a weight, R, being fastened on the upper end of the arm Q. The shaft is also provided with 65 an arm, S, projecting toward the steam-chest, and with an arm, S', projecting in the opposite direction, which arm S' is provided in its free end with an anti-friction roller, s. A float, T, contained in the vessel A, is provided 70 with an upwardly-projecting rod, U, passing loosely through a neck, V, in the cover of the vessel A, which rod is provided on its upper end with a head, W. The rod U is so arranged that its head can strike the end of the 75 arm S'. Steam is admitted into the steam-chest J by a pipe coupled to the same at Y.

The operation is as follows: If the parts are in the position shown, the steam acts on the top of the piston in the cylinder H, and holds 80 the pump-piston F down. When the level of the water rises sufficiently, the float T rises, and the head W of the rod U strikes against the end of the arm S', thereby swinging the upper end of the arm Q in the direction of 85 the arrow a'. When the upper end of the said arm passes the vertical line, the weight R throws it downward in the direction of the arrow a', and the end of the arm strikes the upper end of the rod L, and drives the same 90 downward, thereby moving the valve K downward, and thus admitting steam to the lower end of the cylinder. The steam raises the piston in the cylinder H, the piston-rod G, the pump-piston F, and the arm N. As the 95 arm N rises, its bottom tappet, O', strikes the arm S, and throws the arm Q in the inverse direction of the arrow a', whereby the end of the bottom arm, Q', strikes the lower end of the bottom rod, L', and drives the valve K 100 upward, thereby admitting steam into the top of the cylinder H, whereby the pump-piston F is forced downward. The upper tappet, O, against which the arm S strikes, prevents the

arm Q from swinging too far in the inverse direction of the arrow a'. As the pump-piston rises it draws the water through the pipe C into the pump-cylinder, and when the pump-piston descends it forces the water into the boiler. The level of the water in the vessel A has thus been lowered, and as soon as the level of the water rises again sufficiently to cause the head W on the rod U to strike the arm S' the above-described operation is repeated. The device operates automatically in all respects.

The water conducted into the vessel A need not necessarily be condensation-water, but can be derived from any other suitable source.

Having thus described my invention, I claim as new and desire to secure by Letters Patent—

1. A boiler-feeder constructed substantially as herein shown and described, and consisting of a pump connected with a vessel for receiving water, which vessel is provided with a float adapted to throw a weighted lever for adjusting the valve of the steam-cylinder of the pump in such a manner that the pump will operate as set forth.

2. In a boiler-feeder, the combination, with a steam-pump and a vessel adapted to receive water, of a float in the said vessel, a slide-valve for governing the entrance of steam to the steam-cylinder of the pump, rods projecting from the top and bottom of the valve, a float in the vessel, a weighted rocking lever

adapted to be thrown by a rod on the float and adapted to adjust the slide-valve by striking the ends of the rods of the same, substantially as herein shown and described, and for the purpose set forth.

3. In a boiler-feeder, the combination, with a steam-pump and a vessel for receiving water, of a float in the vessel, a slide-valve connected with the steam-cylinder of the pump, rods projecting from the top and bottom of the valve, a weighted rocking lever adapted to be thrown by a rod on the float, and adapted to move the slide-valve, and an arm secured to the top of the pump-piston rod, and provided with tappets for throwing the weighted lever back into position, substantially as herein shown and described, and for the purpose set forth.

4. In a boiler-feeder, the combination, with the vessel A and its float T, of the steam-pump D F G H, the steam-chest J, the slide-valve K, the rods L L', the shaft P, having arms Q Q' S S', the arm N, having tappets O O', the weight R, and the rod U on the float T, substantially as herein shown and described, and for the purpose set forth.

JOHN H. PHILLIPS.
